UNITED STATES PATENT OFFICE.

INNES T. VERDIN, OF CINCINNATI, OHIO, ASSIGNOR TO THE VERDIN KAPPES & VERDIN COMPANY, OF CINCINNATI, OHIO, A CORPORATION OF OHIO.

POWER-MECHANISM TRIP DEVICE.

Application filed May 12, 1920. Serial No. 380,753.

To all whom it may concern:

Be it known that I, INNES T. VERDIN, a citizen of the United States of America, and a resident of Cincinnati, in the county of Hamilton and State of Ohio, have invented a new and useful Improvement in Power Mechanism Trip Devices, of which the following is a specification.

An object of my invention is to provide 10 a trip device for such mechanisms as punch presses, that will require that the operator use both hands to trip the mechanism, avoiding the possibility of the operator having one hand exposed to the mechanism when 15 it is tripped.

Another object of my invention is to provide a device wherein the hand mechanisms employed, for the purpose stated, are not attached to one another.

20 Another object is to provide a trip device that is simple in construction and operation, and in which the possibility of accidental tripping is reduced to a minimum.

These and other objects are attained by 25 means described herein and disclosed in the accompanying drawing in which:

Fig. 1 is a side elevation, parts being broken away, of a punch press embodying my invention.

30 Fig. 2 is an enlarged sectional view on line 2—2 of Fig. 1.

Fig. 3 is an enlarged side elevation of a tripping mechanism, forming a detail of my invention.

35 Fig. 4 is a sectional view on line 4—4 of Fig. 3.

Fig. 5 is an enlarged sectional view on line 5—5 of Fig. 1.

Fig. 6 is a perspective view of a U fastener, showing in dotted lines the manner of 40 attachment of the fixed handles, the fastener and handle forming details of my invention.

Fig. 7 is an enlarged sectional view on 45 line 7—7 of Fig. 1, showing the means and method of attachment of the loose handle to the shaft, all which form details of my invention.

My invention is of a tripping mechanism 50 and comprises right and left handles that may be moved independently of one another, but which are so arranged that they cooperate in tripping the press when they are jointly operated. The trip mechanism 55 comprises a trip roller f^3 mounted on a trip

arm f that is pivotally attached to a trip bar F . The trip rods l and r , attached to the right and left handles are secured to the trip blocks D and D' mounted on the press in such relation to the trip arm and trip 60 roller that when both trip handles are moved, the blocks will operate upon the trip arm and trip roller thereby moving the trip bar attached to the clutch on the press. The trip blocks are so arranged that unless both 65 of the blocks are moved, the trip bar will not be affected.

The punch press A comprises the customary frame having the uprights a and a' and bolster a^2 .

70 The shaft B is mounted horizontally upon the uprights a and a' and extends through them. The right handle R is mounted upon and secured to the shaft B. The left handle L is loosely mounted on the shaft B. The 75 collars b mounted on the shaft B prevent any lateral motion of the shaft B.

The lever R' is mounted upon and secured to the shaft B adjacent to the left handle L, being spaced therefrom by means of the 80 collar b' mounted on the shaft B. The collar b^2 mounted upon and secured to the shaft B holds the left lever upon the shaft B. The springs b^3 , b^4 and b^5 are attached to the uprights of the frame and to the handles 85 L and R and to the lever R' respectively. The upper ends of the trip rods l and r are attached to the shanks d and d' formed on the blocks D and D' . The trip rods are attached at their lower ends to the handle L 90 and the lever R' respectively by means of the collar l' . (See Fig. 5.)

A shank l^3 is formed on the collar l' . A pin l^4 pivotally mounted upon shank l^3 is secured in position by the cotter pin l^5 . A 95 shoulder l^6 formed on the pin l^4 limits the distance to which the pin l^4 extends through the shank l^3 . The trip rods are adapted to be adjusted in a slot l^7 in the pin l^4 . The screw l^8 secures the trip rod to the pin after 100 the adjustment has been made.

The handle R and the lever R' are mounted upon the shaft B in the manner and by the means disclosed in Fig. 6. The U fastener R^2 has its sides r^1 and r^2 spaced to permit the bar forming the handle R to be adjusted longitudinally between them. The sides of the fastener are slotted, the slots having a flat side, whereby the fastener 105 when mounted upon the shaft B, will be 110

precluded from rotating about the shaft B because of the mutilated or flat surface b^6 on the shaft B. The handle engages the flat surface b^6 and the inside surface of the base 5 of the U fastener. The screw r^3 is adapted to pass through the base of the fastener and to clamp the handle R upon the shaft B.

The handle L is mounted on the shaft B in the manner and by the means disclosed in 10 Fig. 7. The block K has a slot k in which the bar forming the handle L can be longitudinally adjusted. The screw k' extends through the wall of the block, engaging the handle L and secures the handle in the block. 15 A slot k^2 , extending through the block transversely to the slot k is adapted to permit the block to be loosely mounted upon the shaft B.

The blocks D and D' are mounted in a 20 housing E attached to the frame of the punch A. The block D' has a shank d' formed on its lower end and has a slot d^2 formed in the shank. A pin e extends from the housing E into the slot d^2 . The 25 trip rods l and r have their upper ends l^4 and r^4 turned in such way that they will extend through apertures d^3 formed in the shanks d and d' . Cotter pins l^5 and r^5 prevent disengagement of the trip rods and 30 the blocks. The inclined face d^4 , formed on the block D', extends upwardly toward the block D, and terminates immediately adjacent to a similar surface formed on the block D.

35 The trip bar F is mounted between the blocks D and D' and the back e' of the housing E, and is adapted to be vertically reciprocated. The trip arm f is pivotally mounted upon the trip bar F by means of 40 the screw f' , and is spaced from the trip bar by the collar f^2 through which the screw f' extends before engaging the trip bar. The trip arm extends upward from the collar f^2 , and has a trip roller f^3 mounted 45 at its upper end on pivot f^5 . The trip roller f^3 normally engages the inclined surfaces d^4 formed on the blocks D and D'.

A spring G, mounted upon the shank F' 50 formed on the lower end of the trip bar, engages the shoulder f^4 formed on the trip bar and the bottom e^2 of the housing, normally holding the roller in contact with the inclined surfaces d^4 . The trip bar F is at 55 its upper end attached to a clutch, not shown, of the type that is commonly used on punch presses.

The operation of my device is as follows: After the article to be worked upon has been fixed upon the bolster a^2 the operator 60 must press downward upon both the right and left handles to trip the machine. Unless both handles are jointly operated the press will not trip. The reason for this is that, if only one handle is pushed downward the block attached to the trip rod 65

secured to such handle will be pulled downward as such block moves downward, the trip arm and trip roller will be thrown toward the opposite block and will assume the position shown, in Fig. 3, in dotted lines. 70 This will have no effect upon the trip bar F. When the handles are operated jointly the trip bar is moved downward because the trip collar is secured between the inclined surface d^4 on the blocks D and D' and consequently the downward movement of the blocks is transmitted to the trip bar by means of the trip arm f. The spring G will return the trip bar and the trip blocks to their normal position as soon as the 80 handles are released. The springs b^3 , b^4 and b^5 return the handles L and R and the lever R' respectively to their normal position, thereby relieving the spring G from the weight of the handles, and giving lateral 85 support to the ends of such handles.

The handles, lever and the trip rods may be adjusted in relation to one another and in relation to the bar B, thereby making it possible to move the handles and trip rod 90 so that they will not interfere with any material that is to be worked upon. The adjustment of the trip rod in relation to the handle L and lever R' is made by loosening the screws l^2 and l^3 , the screw l^2 controlling 95 the longitudinal movement of the collar l^7 on the handle and lever, and the screw l^3 controlling the longitudinal movement of the trip rods through the eye l^7 formed in pin l^4 attached to the collar l^7 . The handle 100 L is adjustable longitudinally and in relation to the shaft B by loosening the screw k' in the block K. The block can be adjusted horizontally upon the shaft B by moving the collars b^1 and b^2 . The handle 105 R and lever R' are adjustable longitudinally in relation to the bar B by loosening the screw r^3 . The shank F' may be attached to a foot lever by means of the chain H, and the device operated by means of the foot 110 lever. The chain H can be readily attached to or detached from the trip bar by means of the hook h.

What I claim is:

1. In a clutch tripping device the combination with a trip bar, of means adapted to be reciprocated in parallelism and having centrally converging surfaces, means mounted on the trip bar and comprising a trip arm, a trip roller, and pivots connecting the trip arm to the bar and the roller to the arm, the arm and the roller being adapted to normally take a position in alignment with the point of convergence of the inclined surfaces and to be moved 125 from such alignment by the movement of one of the reciprocating means, and to be reciprocated in parallelism with the reciprocating means by the joint movement of the reciprocating means. 130

2. In a clutch tripping device the combination with a trip bar adapted to be reciprocated, of reciprocating means comprising a housing, reciprocating blocks slidably supported by the housing, a trip arm, a trip roller, pivots connecting the roller to the trip arm and the trip arm to the trip bar, the blocks being adapted to jointly

move the roller and arm in the line of reciprocation of the trip bar, means to individually reciprocate the blocks, and means to return the trip bar to its normal position. 10

In witness whereof, I have hereunto subscribed my name this 10th day of May 1920. 15

INNES T. VERDIN.
